UNITED STATES PATENT OFFICE.

JAMES LEE, OF NEW YORK, N. Y., ASSIGNOR TO HIMSELF AND MILTON FINKLE, OF SAME PLACE.

STEREOSCOPIC APPARATUS.

Specification of Letters Patent No. 22,838, dated February 1, 1859.

To all whom it may concern:

Be it known that I, JAMES LEE, of the city, county, and State of New York, have invented a new and useful Improvement in 5 Stereoscopic Machines; and I hereby declare that the following is a full, clear, and exact description thereof.

Figure 1, is a front sectional view of the machine. Fig. 2, an end view showing the 10 internal arrangement. Fig. 3, a section detached with the arbor. Fig. 4, is a perspective view of my improved adjustable picture holder adapted to hold pictures of various material and thicknesses, and may be attached to other varieties of stereoscopic machines. R, is the frame made of any suitable material, S S are springs with slots at the lower and catches at the upper end making them adjustable to various sizes of 15 pictures and securing them in place, T is the picture. Fig. 5, is a transverse section.

The purpose of this improvement is to combine in one machine, by a simple and economical method an apparatus by which 20 an indefinite number of stereoscopic views may be brought before the object glass with ease and facility.

By referring to Fig. 3, we have a section showing the picture holder F the arbor J, J, 25 a part of the elastic band E, controlling or connecting band H, and hinges I, I.

The arms or holders F's, are made of the proper length and thickness to correspond with the pictures with grooves K, K, at each 30 end to receive the picture.

Upon the under side of the holder there is two projections or hinges I, I, with holes for the purpose of turning upon the arbors J, J. These hinges are placed at distances 35 from the end varying to suit the thickness of each, that they may pass freely by one another, the operation of which is similar to the fan joint as may be seen by reference to I Fig. 2. These holders are connected to each other by a controlling band H, H Fig. 2, and the space is measured so that when one of the holders, as F, is before the object glass as when at P, those adjoining as G, M, will be upon a line near the fulcrum and be- 40 low the line of vision, and which from their own weight tend to a uniform condition. The object of this band is to bring up from

a level, one of the holders into contact with the elastic band E, by which it is carried up to the object glass, and when not in use the 45 band folds down as seen below G, M, Fig. 2.

By lengthening the projections or hinges I, I, fixed to the under side of the holders the circle is increased by which an indefinite 50 number of holders may be used.

F, F, F, F, F, Fig. 2, are duplicates of the section Fig. 3.

N is a grooved flange over which the elastic band E, passes.

In Fig. 1, A is a knob or handle attached 55 to the pulley B. C, C, are two friction rollers and D D are two extension rollers which are used to extend the elastic band, so that the arm of the holders may perform about a three quarter revolution without 60 contact.

The operation of the machine is as follows: by turning the knob A, Fig. 1, motion is given to the large pulley B carrying the elastic band E over the friction rollers C, C, around 65 the expanding rollers D, D, and over the grooved end of the flange of the picture holders seen at N, Fig. 2, moving it forward in the direction of the arrows O, O. As it passes the point P, Fig. 2, the controlling 70 band H draws the holder G in contact with the elastic band E at D, by which it is carried up to the point P, before the object glass, while F, has passed down and taken the place of M, which by its weight has 75 passed to F below, and then by continuing to turn the knob or handle each of the pictures in turn is brought before the eye of the beholder.

I am aware that revolving stereoscopic machines have been in use previous to this time, 80 operated in a variety of ways; one of which is by an endless band patented by Alex. Beckers April 7th 1857 of the city of New York, but to my knowledge there is none constructed and operated upon the principle 85 here claimed.

I therefore claim—

1. The fan or segment hinge I Fig. 2; or 90 its equivalent in combination with the picture holders F F for the purpose specified.

2. I claim the controlling band H, or 95 equivalent for the use herein specified.

3. I claim the elastic band E or its equiva-

lent in combination with the pulley B, and rollers C, C, and D, D, for the purposes specified.

4. I claim the picture holder Figs. 4 and 5 as described, for the purposes set forth.

5. Finally I claim the combination as set forth and described, but do not confine my-

self to the exact proportions as I may vary the same while I obtain the same end by means essentially the same.

JAMES LEE.
